GAS HEATED TOASTING DEVICE

Lester E. Padelford, Buffalo, N. Y., assignor to
The Republic Metalware Company, Buffalo,
N. Y., a corporation of New York

Application February 11, 1930, Serial No. 427,620

9 Claims. (Cl. 126—41)

My invention relates in general to toasting devices, and in particular to that type of toaster in which baskets are carried by chains through the toasting chamber.

5 One of the objects of my invention has been to provide a novel heating chamber for toasting devices.

Another object has been to provide molded heating chamber walls provided with means for holding radiant elements.

10 Another object has been to provide a highly polished reflector for the heat produced by the radiants.

A further object has been to provide radiants 15 having passageways for auxiliary air.

Moreover, the toasting chamber of my device is substantially closed at each side of the bottom thereof, and the burners of the device are designed to pass up through openings formed in 20 the bottom, each opening being of such a relative size that auxiliary air will pass between the opening and burner and be supplied to the burner.

Furthermore, the burners of my device are so 25 designed that a substantially uniform degree of heat is generated clear across the chamber at the plane where the toast is made.

Other objects are to provide a device which 30 shall be very economical in the consumption of gas, and one in which the toast made therein shall be uniformly brown.

The above objects and advantages have been accomplished by the device shown in the accompanying drawings, of which:

35 Fig. 1 is a vertical, sectional elevation of my device.

Fig. 2 is a sectional plan view of the same, taken on line 2—2 of Fig. 1.

40 Fig. 3 is a fragmentary, perspective view of one of the combustion chamber walls, showing the burner and radiant elements.

Fig. 4 is a plan view of one of the cross members for closing off the bottom of the combustion chamber, showing one of the burners secured in 45 place therein.

Fig. 5 is a fragmentary, sectional view taken through the center of one of the burners, showing a portion of the combustion chamber wall and the radiants.

50 Fig. 6 is a rear elevation of one of the radiants.

My device comprises a casing 10 being open at the front side, and having a rear wall 11 and interspaced side walls 12 and 13. A front plate 14 is arranged across the upper part of the front 55 of the casing and behind the upward pass of the

sprocket chains 15. Two sprocket chains are provided, one at each side of the device, and each of them passes over an upper sprocket wheel 16, and two lower sprocket wheels 17 and 18. The sprocket 18 is so arranged below the sprocket 5 16 that the downward pass of the sprocket chains 15 will be in a substantially vertical position within the center of my device. The front plate 14 is inclined backwardly, as shown in the drawings, and the chains 15 follow substantially this inclination. A plurality of toast baskets 22 are carried by the chains, and because of the inclination of the upward pass of the chains, slices of bread may be conveniently placed within the baskets as they are traveling upwardly, the inclination serving 10 to prevent their falling out in the upward passage. The front plate 14 is provided with a curved portion 19, the curvature of which is substantially concentric with the upper sprocket 16. The sprockets 17 and 18 are separated from each other, 20 so that the chains are caused to have a horizontal pass, during which time the baskets are moved to the horizontal position, and the toast discharged therefrom. A curved plate 20 is arranged under the sprocket wheel 18 onto which the toast 25 drops. The plate is inclined upwardly toward the back of the device so that the toast when striking it will be discharged forwardly and deposited within a tray 21 arranged at the front of the device. A wire rack (not shown) may be placed on 30 the bottom of the tray for keeping the finished toast out of contact therewith, whereby "sweating" will be avoided. A suitable motor 25 is provided by which the sprocket wheel 18 at one side of the device is driven, preferably by means of a 35 sprocket chain 26, shown in dotted lines in Fig. 1.

The toasting chamber 30 of my device is provided with two molded oven walls 31 and 32. The wall 31 fits within the front plate 14, and at its upper end within the curved portion 19 40 thereof. The wall 32 at the back of the device is arranged in interspaced relation with the rear wall 11 of the casing, whereby the casing wall is kept relatively cool. Vertically arranged wires 33 extend down into the toasting chamber and 45 are arranged parallel to the downward pass of the chains 15, whereby the slices of bread will be kept from falling into the chamber during their downward passage therethrough. The wires 33 are carried by a framework 34 which is slidably supported in ways 35 carried by the casing and formed also in upstanding arms 36 at the top of the casing. Each of the oven walls is provided with side flanges 40 which serve to close 50 the ends of the toasting chamber. A plate 41 55

of refractory material is arranged at the upper end of the oven wall 32, and extends across the device for the purpose of closing off the space provided for the insertion of the rack 34 carrying the wires 33.

Each of the oven walls is carried by a cross member 42 which extends from a point on each side of the passageway 43 formed through the chamber, to the outside edge of the lower part 10 of the wall. Each of these cross members is provided with a slot 44 through which the top 45 of the burner 46 projects. The top ledges 47 of the burner are arranged in interspaced relation with the bottom of the cross member, so that 15 auxiliary air may pass up between the cross member and the burner ledge. The top of the burner is formed with a longitudinal slit 50 extending from which are a plurality of lateral slits 51. The lateral slits are not uniformly arranged throughout the length of the burner, but a lesser number 20 of them is provided at the center than at the two ends, since it is necessary to provide a greater amount of heat at the ends than at the center. The amount of heat, therefore, generated by each burner will be distributed substantially uniformly throughout the width of the 25 toasting area. Each burner is of the Bunsen type and is, of course, provided with a suitable mixer 52, gas being fed to the mixer by pipes 53 connected with a header 54. Each of the gas burners is suspended from the cross member, and is secured thereto by any suitable means.

The lower portion of the inner surface of each 30 of the oven walls is inclined as shown in the drawings, and the inclined surface carries a number of radiant holders 60. The number of these holders will depend upon the number of slices of bread to be carried by each of the toast baskets 22. In the drawings, I have shown three 35 of such holders. These holders are made of polished metal preferably stainless steel and the exposed surface 61 of each acts as a reflector for the heat generated by the gas burners. Each 40 of these holders is provided with a flange portion 62 which is arranged in interspaced relation with the exposed surface 61 and at a distance sufficient to receive the radiant 63. The upper end 64 of the flange 62 is provided with a slit 65, whereby this upper end may be bent 45 over the top of the radiant so as to hold it in position. The lower end of the radiant holder is provided with an outwardly turned lug 66 which contacts with the lower edge of the radiant.

50 Each of the holders has its lower end 67 bent backwardly at an angle with the exposed surface 61 so as to expose auxiliary air openings 68 formed in the cross member 42.

Each of the radiants 63 is formed in its back 55 with a plurality of longitudinal passageways 70, and a plurality of openings 71 are formed through the face of the radiant and extend from these longitudinal passageways. When the radiant is in position, as shown in Figs. 1 and 3, auxiliary 60 air will pass up through the openings 68 formed in the cross member 42 and into the passageways 70, whence it will pass through the openings 71 to complete combustion at the face of the radiant. The radiants are preferably formed 65 with a plurality of cone-shaped projections 72, which become practically incandescent when the gas is burning and thus aid in the combustion of the gas products. An overhanging flange 73 formed at the top of each of the radiants serves 70 not only to deflect the heat outwardly toward

the bread being toasted, but also provides means for conveniently handling the radiants.

It will be obvious from the above that when the burners 46 are lighted, the premixture of gas and air will burn at the slits 50 and 51. Auxiliary air will be supplied between the ledges 47 of the burners and the bottom surfaces of the cross members 42, which will pass upwardly and mix with the burning gas. A further supply of secondary air will pass through the holes 68 10 formed in the cross members 42 and be supplied to the burning flame at the face of the radiants, as hereinbefore described.

Obviously, some modifications of the details herein shown and described may be made without departing from the spirit of my invention or the scope of the appended claims, and I do not, therefore, wish to be limited to the exact embodiment herein shown and described, the form shown being merely a preferred embodiment thereof. 15

Having thus described my invention, what I claim is:

1. A toasting device comprising a casing, a toasting chamber within the casing, said chamber being formed by oppositely arranged oven 25 walls, refractory radiants carried by the walls and each being formed with longitudinal grooves in its rear face and with openings extending from the grooves to the front face thereof, means for supplying air to the grooves, a burner for 30 heating the radiants, and means for conveying bread to be toasted between the oven walls.

2. A toasting device comprising a casing, a toasting chamber within the casing, said chamber being formed by oppositely arranged oven 35 walls, cross members carried by the casing and supporting the oven walls, a burner carried by each cross member and arranged under each wall, radiants carried by each of the walls and arranged over the burners, each radiant being 40 formed with vertical passageways and holes extending to the face thereof, the cross member being formed with openings, whereby auxiliary air is supplied to the passageways of the radiants, and means for conveying bread to be 45 toasted between the oven walls.

3. A toasting device comprising a casing, a toasting chamber within the casing, said chamber being formed by oppositely arranged oven walls, radiant holders having vertically arranged 50 flanges carried by the walls, radiants carried by the holders, each radiant being formed in its rear face with longitudinal grooves and connecting holes extending through the face of the radiants and communicating with the grooves, 55 means for supplying auxiliary air between the radiants and radiant holders, a burner arranged under the radiants, and means for conveying bread to be toasted between the oven walls.

4. A toasting device comprising a casing, a 60 toasting chamber within the casing, the chamber being formed by oppositely arranged oven walls, sprocket chains carried by the casing, and a plurality of toast baskets rigidly attached to the sprocket chains, the downward passes of the 65 chains being substantially vertical and extending through the toasting chamber, and the upward passes thereof being inclined rearwardly and being exposed on the exterior of the casing, whereby toast placed within the baskets on the 70 upward pass will be retained in position and then passed downwardly through the toasting chamber.

5. A toasting device comprising a casing, a toasting chamber within the casing, said chamber 75

ber being formed by oppositely arranged oven walls, polished metallic reflectors carried by the walls, refractory radiants carried by the reflectors, each radiant being formed with longitudinal grooves in its rear face and with openings extending from the grooves to the face of the radiant, means for supplying air to the grooves, and burners arranged under the radiants.

6. A toasting device comprising a casing, a toasting chamber within the casing, said toasting chamber being formed by oppositely arranged refractory oven walls, a polished metallic plate carried by and in contact with the inner face of each refractory wall, a refractory radiant adjacent to each metallic plate and formed with a plurality of openings, burners for heating the radiants, and means for conducting air between the metallic plates and their adjacent radiants.

7. A toasting device comprising a casing, a toasting chamber within the casing, said chamber being formed by oppositely arranged oven walls, radiants carried by the walls, and burners for heating the radiants, each burner being provided with a plurality of openings, the combined area of the openings formed in the central portion of the burner being less than the combined area of the openings formed in each end portion of the burner.

8. A toasting device comprising a casing, a toasting chamber within the casing, said chamber being formed by oppositely arranged oven walls, radiants carried by the walls, and burners for heating the radiants, each burner being formed with a longitudinal slit and with a plurality of lateral slits communicating with the longitudinal slit, a greater number of lateral slits being provided within a certain length at each end portion of the burner and a smaller number of slits within the same length intermediate the end portions.

9. A toasting apparatus comprising a pair of spaced, upwardly extending heating elements, a single supporting sprocket at each side of the apparatus and arranged above one of said heaters, two endless chains supported on said sprockets, the upward passes of said chains being exposed and inclined and the downward passes being substantially vertical and passing through between the heaters, and flat baskets rigidly mounted at successive intervals on said chains and extending outwardly therefrom the inclination of the upward passes of the chains being such as to prevent slices of bread from falling out of the baskets during the upward inclined movement thereof.

LESTER E. PADELFORD.
